UNITED STATES PATENT OFFICE.

WILLIAM H. GARLAND, OF CHELSEA, MASSACHUSETTS, ASSIGNOR TO THE THOMSON-HOUSTON ELECTRIC COMPANY, OF CONNECTICUT.

ELECTRIC CONNECTOR.

SPECIFICATION forming part of Letters Patent No. 470,820, dated March 15, 1892.

Application filed November 23, 1891. Serial No. 412,707. (No model.)

To all whom it may concern:

Be it known that I, WILLIAM H. GARLAND, a citizen of the United States, residing at Chelsea, county of Suffolk, State of Massachusetts, 5 have invented a certain new and useful Improvement in Electric Connectors, of which the following is a specification.

This invention relates to improvements in electric connectors for railway-rails, and is 10 adapted for use in any case where the rails are utilized as part of an electric circuit—as, for example, in connecting the ends of electric-railway rails—so as to form a permanent and reliable return connection for the operating- 15 current.

My improved connector comprises a bond or strip, preferably a short section of wire, and two terminal sleeves adapted to slip over the ends of such strip and to be inserted in 20 punched or bored holes in the ends of the rails, so that when the sleeves with their contained wire ends are forcibly driven into the holes provided therefor in the rails they will jam and bind against the ends of the wire and 25 make a tight and practically-permanent connection.

The present invention consists in making the perforation or hole through the sleeve which receives the wire eccentric to the axis 30 of the pin, so as to leave a comparatively thin and yielding wall at one side of the sleeve, while not detracting from the strength and solidity of the sleeve as a whole. At the same time the wall, not being cut through, moisture and dirt are effectually excluded from the 35 joint between the wire and sleeve and a permanent connection thus insured.

In the accompanying drawings, Figure 1 shows my connector as it appears when the 40 wire has been passed through the rail and into the sleeve, but before the latter has been driven into the hole prepared therefor in the rail, the said rail being shown in section. Fig. 2 is a similar view showing the plug driven 45 into the rail, completing the connection. Fig. 3 is an end view of the plug or sleeve. Fig. 4 is a cross-section of the same with the wire contained therein. Fig. 5 is a section of a portion of the rail, showing the plug and wire 50 embedded therein. Fig. 6 is a longitudinal

section of the sleeve, and Fig. 7 is a side elevation thereof.

The usual connecting strip or wire *b* is employed by me to form an electric connection between adjacent ends of the rail *a*, and the 55 rails are perforated, as usual, near their ends, the perforations or holes *a'* being somewhat larger than the connecting-wire.

The plug or sleeve, which in my invention forms the connection between the wire *b* and the rail *a*, consists of a sleeve or cylinder *c* of metal, having a bore or longitudinal perforation eccentric to its axis, so as to leave a thin and yielding wall *c'* on one side thereof. This wall is, however, continuous, as shown. The 60 diameter of the sleeve and of its bore are such as to enable it to tightly fill the space between the wire and the rail, as hereinafter described.

In applying my connector to a railway-rail, the latter having been properly perforated, an 70 end of the strip or connecting-wire is passed through the perforation in the rail, the tube or sleeve *c* is slipped over the end of said strip, and the sleeve or plug, with its contained wire end, is then driven into the perforation 75 in the rail, the thin or yielding wall of the plug being compressed against the wire, making a tight and effective joint. The end of the sleeve or plug which enters the rail first is preferably tapered, as shown at *c*², so as to 80 facilitate its entrance.

It is obvious that the form of the hole in the sleeve may be varied and that the sleeve itself need not be of the precise form shown—for example, its exterior is not necessarily 85 cylindrical, but may have any usual or desired form. The taper may be extended substantially the whole length of the plug, and other minor variations be made without deviating from my invention. It is also apparent 90 that this connector may be used to make a joint between conductors of various kinds and in various locations, especially when one of the conductors to be connected is larger than the other.

The main feature of my invention is the location of the channel which receives the smaller conductor out of line with the axis of the connecting-piece, so that one side of the piece furnishes a solid driving-plug, while the 95 100

other side is more yielding and readily compressible against the smaller conductor.

What I claim as new, and desire to secure by Letters Patent, is—

- 5 1. An electric connecting-plug consisting of a sleeve or tube with its bore eccentric to its axis, leaving a thin and comparatively yielding wall on one side of the tube.
- 10 2. The combination, with the conductor having a perforation or opening and the connecting-wire smaller than said opening, of the sleeve or plug driven into said opening, having a longitudinal bore eccentric to its axis and receiving said wire.
- 15 3. The combination, with a perforated conductor, of the sleeve driven into said perforation and having a longitudinal bore eccentric to its axis, leaving a thin and yielding wall in one side of the sleeve and a connecting-conductor contained in said longitudinal bore.
- 20

4. The combination, with the perforated conductor and a smaller conductor, of a sleeve driven into the perforation, having a longitudinal bore receiving the smaller conductor and having a portion of its wall thinner than ²⁵ the rest, so as to yield and be compressed against said conductor.

5. The combination, with the perforated conductor, the connecting-conductor smaller than such perforation and passing into the ³⁰ same, of a connecting-piece between such conductors having a channel receiving the smaller conductor, said channel being nearer one side of the piece than the other.

In witness whereof I have hereunto set my 35
hand this 18th day of November, 1891.

WILLIAM H. GARLAND.
